2 Claims. (Cl. 60—51)

This invention relates to a system for controlling a hydraulic pressing apparatus. The most desirable characteristics for hydraulic equipment, such as oil presses, are (1), large pressing capacity, (2), short operating time and (3), large output out of small input. There has long been a keen desire for such hydraulic equipment as presses and the like, to have these three characteristics at one time.

In this invention, this desire has been fulfilled by introducing into the system of hydraulic apparatus, a conventional pump of any type, a set of pressure hydraulic accumulators, a hydraulic tank, a control valve, electromagnetic change-over valves, a hydraulically operated communicating valve and two automatic pressure control switches, and by letting all these valves act correlatedly with each other by operating an operating lever, to supply or exhaust, selectively, pressure or non-pressure fluid into or out of a main cylinder and auxiliary cylinders of a hydraulic machine and thus making the main ram or auxiliary rams operate in multistage strokes.

One of the embodiments of this invention is illustrated in the drawings, and its operation and superior characteristics are explained in the following descriptions.

In the drawings: FIG. 1 shows the apparatus of this invention applied to a hydraulic press; FIG. 2 shows communication between fluid pipes in a control valve; FIG. 3 show diagrammatically the electric circuits connecting the switches; FIG. 3-1 being a front view of the guide plate and control lever, FIG. 3-2 being a side elevational view of the guide plate and control lever, and FIG. 3-3 showing the electrical connections; and FIG. 4 is a table showing the correlations between the electrical connections and valve positions of the electro-magnetic change-over valves 33 and 36.

In FIG. 1, a main cylinder 1 and two auxiliary cylinders 2, being rigidly connected with each other or being made of one block and also being rigidly and properly fastened to their frame and bed plate 3 constitute a hydraulic press.

A single acting ram 4 of the main cylinder 1 and two double acting rams 5 of the two auxiliary cylinders 2 are all fastened to a press plate 6. A control valve 7 consists of a piston valve 8, having piston heads h_1 and h_2 and a valve cylinder 9. This piston valve is connected by a connecting rod 10 and pins 14₁ and 14₂ to an operating lever 12, whose one end is joined by a pin 11 to a guide plate 13.

Each of oil pipes 15, 16, 17, 18 and 19 has an opening inside the wall of the control valve cylinder 9.

These openings are opened or shut by the piston heads h_1 and h_2 , when the piston valve 8 is shifted to the right or left, through the connecting rod 10 by the operating lever 12, which is pivoted about the pin 11 to take its position A, O, B, C or D, each designated on the guide plate 13. Thus the pipes above mentioned are connected or disconnected with each other. These connections are shown in FIG. 2, which will be explained later.

An oil pump 28 sucks oil out of an oil tank 35 through an oil pipe 20, and delivers pressure oil through an oil pipe 15 to the control valve 7, and then through an oil pipe 16 to a set of pressure oil accumulators 32 which are connected to this pipe. Pressure oil is thus accumulated in the accumulators, and then it is supplied to the main

2

cylinder 1 and auxiliary cylinders 2, again through the oil pipe 16, control valve 7 etc., or through a branch of the pipe 16 and an electro magnetic change-over valve 33 or 36, which may be either of a rotary type as shown in FIG. 1 or of a piston type, both of which are electromagnetically operated as will be described later.

An electromagnetic clutch 30 couples the oil pump 28 with an electric motor 29. An automatic normal pressure control switch 31 is connected to the pressure oil accumulators 32, and opens or closes the electric circuit of the clutch 30, as the oil pressure reaches its upper or lower limit of normal oil pressure. Thus the magnetic clutch 30 couples or uncouples the pump with the motor so as to keep normal oil pressure automatically in the accumulators.

Similarly an automatic high pressure control switch 37, whose oil circuit is directly connected to a delivery pipe 15 of oil pump 28, for the electromagnetic clutch 30, closes or opens the electric circuit of clutch 30 to keep the oil pressure of pump delivery at a certain higher pressure than the normal, and to supply this high pressure oil directly to the main cylinder 1 from the pump, when communication of oil between the main cylinder and accumulators is cut off.

25 Oil pipes 17 and 22 connect the control valve cylinder 9 and main cylinder 1.

An oil pipe 18 connects the control valve cylinder 9 and the lower chambers of auxiliary cylinders 2.

A surge valve 34, provided between oil pipes 22 and 27 which connect an oil tank 35 and main cylinder 1, is so constructed that the valve opens to connect this tank and main cylinder so as to permit non pressure oil to flow freely between the two, when pressure oil is supplied to operating means for the valve through an electromagnetic change-over valve 33 and oil pipe 21, and that the valve 34 cuts off the communication of oil between the main cylinder and oil tank, when pressure oil is released from the operating means for the valve and is exhausted to the oil tank through the oil pipe 21, change-over valve 33, pipes 24 and 26. This change-over valve 33, when its electric circuit is closed, connects the operating means for the surge valve with pressure oil accumulators 32 through oil pipes 16 and 21, and when its electric circuit is opened, the valve connects the operating means for the surge valve with the oil tank 35 through oil pipes 21, 24 and 26.

Another electromagnetic change-over valve 36, when its electric circuit is closed, connects the upper chambers of auxiliary cylinders 2 with pressure oil accumulators 32 through oil pipes 16 and 23 to supply pressure oil to the cylinders, and when the circuit is opened, the valve connects the cylinders to the oil tank 35 through oil pipes 23, 25 and 26 to exhaust oil from the cylinders.

The operating lever 12 and the guide plate 13 compose 55 a control switch assembly as shown in the FIG. 3.

The guide plate 13 has a set of a pair of contact pieces 51, electrically connected with each other, three contact pieces 52, 53 and 54; while the operating lever 12 has another set of contact pieces 51', 52', 53' and 54'. Each

60 of the contact pieces of the former set contacts with each other of those of the latter, so that the pieces 51, 52, 53 and 54 mate respectively with the contact pieces 51', 52', 53' and 54', and compose four switches, to close or open the circuits of the electro-magnetic change-over valves

65 33 and 36, of the master switch for the normal pressure switch 31 and of the master switch for the high pressure switch 37.

The pair of contact pieces 51, provided at the raising position A and the lowering position B of the guide plate 13 and the contact piece 51' on the control lever 12 compose a switch for the electric circuit of the electromagnetic

change-over valve 33; the contact piece 52 provided along the lowering position B, the normal press position C and the strong press position D of the guide plate and the contact piece 52' provided on the control lever 12 compose a switch for the electric circuit of the electromagnetic change-over valve 36; the contact piece 53 which is provided along the raised position A, the stop and preparatory position O, the lowering position B, and the normal press position C of the guide plate and the contact piece 53' provided on the control lever 12 compose a switch for the electric circuit of the master switch of the normal pressure control switch 31 for the magnetic clutch 30 which couples the oil pump 28 with the electric motor 29.

The contact piece 54 provided at the strong position D of the guide plate and the contact piece 54' provided on the control lever 12, compose the master switch of the high pressure control switch 37 also for the magnetic clutch 30.

The arrangement of control switch assembly and the electric connections between the switches, the change-over valves 33 and 36, the normal pressure control switch 31 and the high pressure control switch 37 together with the magnetic clutch 30, are diagrammatically shown in the FIG. 3. In the FIG. 3, the FIG. 3-1 is the front view of the guide plate 13 and the control lever 12, where the latter is shown by broken lines together with contact pieces provided on it, the FIG. 3-2 is the side sectional view of the above along the position O of the lever 12, and the FIG. 3-3 is the electric connections as above mentioned.

FIG. 4 is a table showing the correlations between the electric connections and valve positions of the electromagnetic change-over valves 33 and 36, and the electric connections of master switches of the normal pressure control switch 31 and of the high pressure control switch 37 for magnetic clutch 30, at each position of the operating lever 12.

An embodiment of the present hydraulic apparatus as applied to an oil press is explained below. This oil press is able to complete its pressing operation, consisting of five strokes, i.e., stop and preparatory, raising, lowering, normal press and strong press strokes, and attains the desired characteristics as follows:

(1) Stop and Preparatory Stroke

The operating lever 12 is set to the position O then as shown in FIG. 2-1, in the control cylinder 9, the opening of the oil pipe 17 to the main cylinder 1 is shut by the piston head h_1 of the piston valve 8.

The operating lever being at this position O, the electric circuit of the electromagnetic change-over valve 33 is opened, and communication between the main cylinder 1 and oil tank 35 through oil pipes 22 and 27 is cut off by the surge valve 34. At this position, the electric circuit of another electromagnetic change-over valve 36 is also open, to cut off the upper chambers of auxiliary cylinders 2 from pressure oil accumulators 32 and to connect the cylinders with oil tank 35.

Also, in the control valve cylinder, the opening of oil pipe 18 to the lower chambers of auxiliary cylinders is shut by the piston head h_2 .

Thus there is no oil flow into or out of the cylinders, and the rams do not move but remain at their present position.

Also at this position O, the openings of the oil pipe 15 from the oil pump, and of oil pipe 16 to the pressure oil accumulators 32 are both opened and communicate with each other in the control valve cylinder 9 between the two piston heads h_1 and h_2 . Thus the pressure oil to be accumulated is pumped into the pressure oil accumulators through the control valve. With the operating lever, at its position O, the master switch of automatic normal pressure control switch 31 closes. Thus

the oil in the accumulators is kept at its normal pressure, and now the press is ready to work.

(2) Raising Stroke

In order to apply a piece to be pressed to the press, the operating lever 12 is shifted from O to its raising position A. Then the control piston valve 8 takes the position as shown in FIG. 2-2, with the opening of the oil pipe 17 to the main cylinder 1 still being closed, and the openings of pipes 15, 16 and 18 are opened to communicate with each other between the two piston heads h_1 and h_2 in the control valve cylinder 9. Thus pressure oil is supplied from the pressure oil accumulators to the lower chambers of auxiliary cylinders 2 to push rams 5 upwards, while the upper chambers are connected with the oil tank 35 through the pipe 23, the electromagnetic change-over valve 36 whose electric circuit is open at this position A of the operating lever, the pipes 25 and 26. Thus the oil in the upper chambers can be exhausted to the oil tank 35 as the auxiliary rams are raised by pressure oil which is supplied into the lower chambers as above described.

On the other hand, the switch *a* for the electromagnetic valve 33 being closed, this valve connects pipes 16 and 21 to supply pressure oil to the operating means for surge valve 34, to connect main cylinder 1 with oil tank 35, and allow oil to escape freely from the cylinder to the tank as the main ram 4 is raised upwards.

Thus the press plate 6 is raised to a desired height, 30 when the operating lever is shifted back to its stop position O, to keep the press plate 6 at its desired height.

(3) Lowering Stroke

The operating lever 12 is shifted from O to the lowering position B, then the control valve piston 8 takes the position as shown in FIGS. 2-3. In this position, the difference in the connection of the pipes in the control valve cylinder 9 between this stroke and that of the raising stroke is that pipe 18 which connects with the lower chambers of auxiliary cylinders 2 now communicates with the port of exhaust pipe 19, whereas previously pipe 18 communicated with pressure oil pipes 15 and 16. Therefore, the oil in the lower chambers of auxiliary cylinders 2 may freely escape to the oil tank 35 through the pipe 18, the control valve cylinder and then the pipe 19. The upper chambers of the auxiliary cylinders 2 connect with pressure oil accumulators 32 through the pipes 23, the electromagnetic change-over valve 36, whose electric circuit is closed by the switch *b* at the position B of the operating lever 12, and pipe 16.

In this position, as the rams are lowered downward, non pressure oil flows freely into the main cylinder from the oil tank through the pipe 27, surge valve 34 and pipe 22, since the surge valve is kept open as described in the raising stroke.

Thus, as the auxiliary rams are lowered by pressure oil supplied to the upper chambers of the auxiliary cylinders, oil in the lower chambers of the auxiliary cylinders is exhausted to the oil tank, and non pressure oil flows into the main cylinder as its ram is lowered.

It is clear, in this stroke, that the rams being lowered by pressure oil in the auxiliary cylinders, finish this stroke much quicker than when they are lowered by their own weight, as in the case of conventional hydraulic presses. 65 Moreover, this stroke is economical, because the amount of pressure oil, which is consumed only by auxiliary cylinders, is very small.

Thus, the rams are lowered until the press plate 6 touches the piece pressed. Then the operating lever 12 is shifted to its position C for the next normal press stroke.

(4) Normal Press Stroke

The operating lever 12 is shifted from B to the normal press position C. Then the switch *c* and the master switch for automatic normal pressure control switch 31

are closed, and the control valve piston 8 takes the position as shown in FIG. 2-4. In this case, the difference in communication of pipes in the control valve cylinder from the lowering stroke, is that the port of pipe 17 is opened in this stroke instead of being shut by the piston head h_1 as in the lowering stroke and this pipe is connected with pipes 15 and 16.

At this position of the operating lever, the electric circuit of the electromagnetic change-over valve 33 is opened to cut off the communication between the main cylinder and oil tank by surge valve 34, and just as in the case in the lowering stroke, the electric circuit of electromagnetic change-over valve 36 is closed to communicate pressure oil to the upper chambers of auxiliary cylinders.

Thus, normal pressure oil controlled by automatic switch 31 is supplied to the main cylinder 1 from the pressure oil accumulators 32 through the pipe 16, control valve 7, oil pipes 17 and 22, and to the upper chambers of auxiliary cylinders 2 as in the case of the lowering stroke to complete this stroke.

(5) Strong Press Stroke

In the four strokes above described, oil pressure is controlled by the normal pressure control switch 31, and therefore, the capacity of the press is normal.

Larger pressing capacity, when required, may be obtained by higher oil pressure, which is controlled by another automatic strong pressure control switch 37.

In this stroke, the operating lever 12 is shifted from C to D. Then the switch d closes the circuits of electromagnetic change-over valve 36 and the master switch for automatic strong pressure control switch 37. In the control valve 7 the opening of pipe 16 is shut by the piston head h_2 to cut off the communication between the oil pump and accumulators, while other pipe openings and their relative communications remain the same as in the normal press stroke as shown in FIG. 2-5.

Thus, oil of higher pressure, controlled by the control switch 37 is supplied directly to the main cylinder 1 from the oil pump 28 through the pipe 15, control valve 7, pipes 17 and 22; and in addition to this accumulated oil is supplied from the accumulators 32 through the pipe 16, change-over valve 36 and pipes 23, to the upper chambers of auxiliary cylinders 2 giving strong overload pressing power to the press plate 6.

When the normal or strong press stroke is thus completed, the operating lever is to be shifted again to its position A for the raising stroke to repeat the same cycle.

In this hydraulic operating apparatus, as above described, a set of pressure oil accumulators of ample capacity is supplied in the oil circuit to enlarge the capacity of the pressure oil source, so that a large amount of pressure oil can be supplied at one time to the press cylinders, with an oil pump of small capacity.

Therefore, by introducing an oil pump of small capacity and of any type, and by introducing a set of pressure oil accumulators into the oil system of a hydraulic press, and by the correlative actions of a control valve, two change-over valves, a surge valve and two automatic pressure control switches, pressure oil of two different pressures from the two systems of oil sources may be supplied to the main and/or auxiliary cylinders selectively, and

thus, a series of multistage strokes of speedy, efficient and powerful pressing operations may be obtained at low initial cost and low running expenses.

It is obvious that the application of this hydraulic apparatus is not limited to a hydraulic press as above described, and that this may be applied to other equipment such as moulding machine, machine tools etc.

I claim:

1. A hydraulic press comprising a main cylinder and at least one auxiliary cylinder, a set of pressure oil accumulators, an oil pump, a motor, a magnetic clutch, said pump being driven by said motor through said magnetic clutch to charge said accumulators with oil of normal pressure, an automatic normal pressure control switch for controlling said magnetic clutch to effect normal pressure output, said pump also acting to charge said main cylinder directly with oil of high pressure, an automatic high pressure control switch for controlling said magnetic clutch to effect high pressure output, an oil tank, a set of change-over apparatus consisting of a control valve, two electro-magnetic change-over valves, master switches for said change-over valves, a surge valve and a control lever equipped with a connecting rod, said control lever acting to operate said control valve, and with electric contacts to close or open correlatedly with the control valve the switches for said electro-magnetic change-over valves, and the master switches for said automatic normal pressure control switch and said automatic high pressure control switch, to connect or disconnect selectively the communication of oil between said oil pump, said oil accumulators, said oil tank and said main and auxiliary cylinders, whereby the rams of said cylinders make a series of multistage strokes of speedy, efficient and powerful pressing powers.
2. A hydraulic press apparatus which consists of a raising means having a control valve between an accumulator provided with an automatic normal pressure control switch and the lower side of an auxiliary cylinder, an oil pressure circuit having an electromagnetic change-over valve between said accumulator and a surge valve, a lowering means having an electromagnetic change-over valve between said accumulator and the upper side of the auxiliary cylinder, a normal press means having said control valve between said accumulator and a main cylinder, a strong press means having said control valve between an oil pump provided with a strong pressure control switch and said main cylinder, and an operating means adapted to selectively or coincidently operate a piston valve of said control valve, said two electromagnetic change-over valves, said automatic normal pressure control switch and said strong pressure control switch respectively, by shifting an operating lever to the respective positions.
